CABINET

John J. Lubberts and Lambert J. Mulder, Grand Rapids, Mich., assignors to Tomlinson of High Point, High Point, N. C., a corporation of North Carolina

Application December 10, 1956, Serial No. 44,123

Term of patent 14 years

(Cl. D33—19)

Figure 1 is a front perspective view of the cabinet embodying our new design, the top surface of the cabinet being preferably provided with a marble insert; and

We claim:

The ornamental design for a cabinet, substantially as shown.
